UNITED STATES PATENT OFFICE.

DELANO D. DUNKLEE, OF GREENFIELD, MASSACHUSETTS.

DESIGN FOR A PHOTOGRAPHIC CARD-MOUNT.

SPECIFICATION forming part of Design No. 27,498, dated August 10, 1897.

Application filed May 12, 1897. Serial No. 636,244. Term of patent 7 years.

To all whom it may concern:

Be it known that I, DELANO D. DUNKLEE, of Greenfield, in the county of Franklin and State of Massachusetts, have invented and 5 produced a certain new and original Design for Photographic Card-Mounts, of which the following is a specification, reference being had to the accompanying drawings, forming a part thereof.

10 Figure 1 represents a side view of a card-mount embodying my design. Fig. 2 represents a section on line 2 2 of Fig. 1.

15 The leading feature of my design comprises a card provided with a bead near and parallel with its edges and having a concavo-convex form in cross-section, said bead forming a continuous ridge or protuberance, which is surrounded by an outer or marginal flat surface and surrounds an inner flat surface, 20 both flat surfaces being in the same plane.

a represents the marginal flat surface.

b represents the bead surrounded by the surface *a*, and *c* represents the flat surface surrounded by the bead.

The bead is substantially equidistant from 25 the margin of the mount along three edges of the latter and is separated from the fourth edge by a wider space.

I claim—

20 The design for a card-mount, substantially 30 as shown and described.

In testimony whereof I have signed my name to this specification, in the presence of two subscribing witnesses, this 10th day of May, A. D. 1897.

DELANO D. DUNKLEE.

Witnesses:

A. J. ROWLAND,
C. A. WHEELER.
